(57) **CLAIM**

The ornamental design for a sidewalk tile, as shown and described.

DESCRIPTION

FIG. 1 is a top plan view of a sidewalk tile of the present invention;

FIG. 2 is a right elevation view of the invention illustrated in FIG. 1;

FIG. 3 is a rear elevation view of the invention illustrated in FIG. 1;

FIG. 4 is a front elevation view of the invention illustrated in FIG. 1;

FIG. 5 is a left elevation view of the invention illustrated in FIG. 1;

FIG. 6 is a bottom plan view of the invention illustrated in FIG. 1;

FIG. 7 is a rear, right, top perspective view of the invention illustrated in FIG. 1; and,

FIG. 8 is cross-sectional view of the invention illustrated in FIG. 1, taken along lines 8-8 of FIG. 1.

The evenly-dashed broken lines in the drawings illustrate portions of the sidewalk tile that form no part of the claimed design.

The symbolic boundary lines shown as dash-dot broken lines on two adjacent sides of the tile depict that any portion of the tile beyond these lines forms no part of the claimed design.
